(57) CLAIM

The ornamental design for a combined liquid and lotion applicator and cover, as shown and described.

DESCRIPTION

FIG. 1 is a front elevation of a combined liquid and lotion applicator and cover showing my new design;

FIG. 2 is a front perspective view of the liquid and lotion applicator shown without the cover for clarity of illustration;

FIG. 3 is a rear elevation of the liquid and lotion applicator shown without the cover and the applicator for clarity of illustration;

FIG. 4 is a bottom plan view of FIG. 3; and,

FIG. 5 is a perspective view of the cover shown separately for clarity of illustration.
